STAMPING DEVICE

Filed Feb. 7, 1927

UNITED STATES PATENT OFFICE

PETER GRABLER, OF ROCKY RIVER, OHIO

STAMPING DEVICE

Application filed February 7, 1927. Serial No. 166,520.

My invention relates to stamping devices generally and particularly to self inking stamping devices which have changeable type.

5 One of the objects of my invention is to provide a simple, inexpensive, substantial, and efficient stamping device.

Another object of my invention is to arrange the elements of a stamping device so 10 that they can be made in quantity and assembled without causing binding between them and without requiring any fitting.

Another object of my invention is to provide a stamping device with means for taking up changes in the type thereof.

Another object of my invention is to provide a lock means for the type adjusting means of a stamping device.

Another object of my invention is to 20 provide a cushioning means for the type of a stamping device near the juncture of the type and an adjacent member of the device.

Other objects will appear or become apparent or obvious during the description of 25 the device shown in the accompanying drawing.

In stamping devices, particularly in those which are self inking, considerable mechanism is necessary; this mechanism in the 30 prior devices gets out of order easily and frequently due to the complicated structure used to attain that mechanism and to the continued pounding action thereon. The present invention aims to provide a stamping device which is light in weight and which does not get out of order easily.

In stamping devices, particularly those which have type on a band or ribbon, the continued use of the prior devices eventually 40 changes the type, as the stretching of the ribbon for instance; this is an undesirable or disadvantageous feature. The present invention aims to prevent the stretching of the ribbon and changes or displacements of the 45 type.

In stamping devices it is quite desirable and advantageous that the device can be manufactured as economically as possible. The present invention aims to so form and 50 arrange and relate members that they can

be made easily and economically and assembled easily and economically and require no fitting in the assembling.

Stamping devices are subjected to continued pounding during the operation or use 55 thereof. In order to retain alignment of the type on such a device it is necessary that the type on the carrier thereof is adjustable. Due to the continued pounding on such devices, the adjustment provided in prior 60 devices does not stay in adjusted position. The present invention aims to retain the adjustment of the type.

In order to illustrate my invention, I have shown the same as embodied in a self inking hand stamp which has type on an endless band or ribbon. I am aware, however, 65 that my invention can be applied to other devices.

In the accompanying drawing:—

Fig. 1 is a perspective view of a self inking hand stamping device with changeable type, embodying the features of my invention. This device is here shown in normal 70 position of the elements with the operating portion of the type against the inking pad.

Fig. 2 is a perspective view of the type frame of Fig. 1 and shows more clearly the one piece structure and formation of this frame and the guide ears and guide means 75 thereon and also shows one of the links as associated with the type frame and with the main frame. For the purpose of more clearly showing the structure, the frame is here shown inverted from its position in Fig. 1; or 80 in other words, is here shown as if it was in stamping position in the device.

Fig. 3 is a perspective view of one of the floating members between the type frame and the type carrier of Fig. 1.

Fig. 4 is a perspective view of the type carrier of Fig. 1 and shows more clearly the one piece structure and formation thereof.

Fig. 5 is a section, taken in a vertical plane indicated by the line 5—5 in Fig. 1, and shows 90 more clearly the relations of the elements.

Fig. 6 is a section, taken in a vertical plane indicated by the line 6—6 in Fig. 5 and shows 95 more clearly the guide means and the relations between the type carrier and the type 100

frame and the adjusting means between them.

Fig. 7 is a perspective view, partly in section, of the type cushioning means between the type carrier and the band of type.

5 Similar reference characters refer to similar parts throughout the views.

The device shown in the accompanying drawing is a self inking hand stamping device having bands of type and comprises, 10 principally, the main frame A, the operating member B, the type frame C, the type carrier D, and the type means E.

The main frame A is formed of one piece of sheet metal with the end walls 10 and 11 15 and the top wall 12 with the bent edges 13 to form the channel or trough wherein the inking pad 14 is mounted.

The operating member B has the handle 15 as well as other features usually found on 20 such devices and necessary or convenient for the operation of the device and also has the legs 16 and 17 extending over the outside of the ends of the frame A.

In order to provide simplicity and inexpensive structure and to prevent parts from 25 getting loose or otherwise getting out of order, I combine parts and form the combination of one piece of material which, naturally, does not get out of order and which 30 can be made with dies which always produce the pieces as substantial duplicates of each other and thereby eliminate the human element of error in assembling as well as in preparing the parts for assembling and also 35 eliminate the necessity of fitting during the assembling or to do any other work thereon previous to the assembling and also eliminate all possibility of parts of an assembly getting loose or shifting from their intended 40 position since there are no parts.

In the present instance, the type frame C is made of one piece of sheet metal and is formed with the base wall 18 having the 45 opening 19 through it; the middle portion of this opening is provided to clear the type and each end of this opening has the guide walls 20, 21, and 22. The flanges 23 are bent from the sides of the wall 18 to stiffen the structure as well as to provide a means for 50 abutting a surface to be printed upon in alignment with and in proper relation to the type.

The legs 24 are bent from the ends of the wall 18, each having the slot 25 and the 55 round hole 26 through it.

The guide ears 27, comprising two oppositely disposed pairs of ears facing each other, are bent inwardly from the legs 24; each ear having the hole 28 through it; the holes 60 28 in each pair of ears being in alignment.

In the present instance, the type carrier D is made of one piece of sheet metal and is formed with the guide members 29 each having the slot 30 through it and with the flanges 65 31 bent outwardly from one end of each mem-

ber 29, each having the journal opening 32 through it, and with the inwardly curved portion 33 connecting the other ends of the members 29 and forming the trough 34 with the open side thereof disposed outwardly 70 from the carrier D. The edges of the guide members 29 fit slidingly between the respective of the ears 27 and between the guide walls 20 and 21 and are guided thereby when the frame C and the carrier D are assembled. The 75 connecting portion 33 extends through the opening 19 in the wall 18 of the frame C when the device is assembled.

In the present instance, the type means E is of a usual structure having three endless type bands or ribbons with type thereon and the adjoining disks for individually adjusting each band as desired. The particular structure of the means E does not, in itself, form a part of the present invention except in so far as it is combined with or related to other parts or elements of the present invention. One end of the type means E is mounted on the shaft 35 the ends of which are mounted in the respective of the guide portions 29. 80

A floating member 36 is disposed between each pair of the ears 27 and each member 36 has a lug 37 on two opposite sides thereof and extending into the respective of the openings 28 in the ears 27 and also has an internally threaded hole 38 in alignment with the journal openings 32 through the flanges 31 when the frame and the carrier are assembled. 85

The lugs 37 are shown rectangular and of the same thickness as the material of which the member 36 is made. This arrangement is the most economical from a production standpoint since one punching operation completes the formation of this member except the tapping of the hole 38. When it is 90 desired to provide leeway for the members 36 so that the same can adjust themselves in the ears 27, the holes 28 may be made larger than the lugs 37. Another expedient, although more expensive than the rectangular lug arrangement mentioned, is to make the lugs 37 and the holes 28 round so that the members 36 are journaled in the ears 27. 95

The walls 39 of the members 36 are spaced from and do not normally contact the inner faces of the ears 27; this arrangement permits the members 36 to float between the ears 27 and this floating feature can be augmented by the loose or by the journaled lugs arranged as described above. 100

The screws 40 are threaded into the respective ones of the holes 38 in the members 36 and are journaled in the respective ones of the journal openings 32 in the flanges 31 of the carrier D and the head of each screw has the serrations 41 and abuts the outside of the respective one of the flanges 31 on the carrier D. 105

The springs 42, coil springs in the present instance, are disposed over the respective ones 110

of the screws 40; one end of each spring abutting one of the members 36 and the other end abutting the inside of one of the flanges 31. This double abutment of the springs tends to move the carrier D in the guides of the frame C and holds the flanges 31 resiliently against the underside of the heads on the screws 40.

The free ends 43 of the wire of the springs 42 extend through the holes 44 in the flanges 31 and engage the serrations 41.

The trough 45 is disposed over and spaced from the trough 34 with the open side of the trough 45 facing the open side of the trough 34. The other end of the type band abuts the closed side of the trough 45.

In the present instance, the means for cushioning the pounding or blows on the type comprises the corrugated spring 46 disposed in and between the two troughs and arranged so that the high points of the corrugations on one side of the spring engage the interior of the trough 34 and the high points of the corrugations on the other side of the spring engage the interior of the trough 45. This arrangement tends to separate the two troughs and thereby takes up all slack in the band type and also relieves the type band from receiving sharp shocks or blows or poundings during the operation and use of the device and thereby not only preserves the type band but also prevents the stretching thereof by eliminating the sharp pounding thereon.

A different kind of a spring, or a different kind of a cushioning means (as rubber for instance), or a different structure may be used to cushion the operating end of the type band.

One end of each of the links 47 is hinged onto the main frame A and has a slot through it comprising the two straight and aligned portions 48 and 49 and the arcuate portion 50 connecting the straight portions. The pins 51 are fixed in the respective one of the links and extend inwardly and into the slots 25 of the legs 24.

The shaft 52 extends through the legs 16 and 17 of the member B, through the slots 53 in the end walls 10 and 11 of the member A, through the slots in the links 47, through the holes 26 in the legs of the member C, through the slots 30 in the guide members of the member D, and through the other end of the type member E.

This arrangement, aided by the spring 54 in the tube 55, normally retains the operating portion of the type bands against the ink pad. When the member B is forced toward the member A, the shaft 52 is moved with it. Due to the shaft being retained in the holes 26 and in the type member E and being slidably in the slots in the links and in the slots 30 and 53, and due to the pins 51 being slidable in the slots 25, the downward movement of the shaft 52, by means of the

member B, first imparts a straight downward movement to the member E due to the straight portions 48 of the slots in the links 47 to remove the operating portion of the member E straight from the inking pad, then imparts a rotative movement to the frame C and the carrier D and the member E and rotates these members half way around due to the pins 51 engaging the arcuate portions 50, and then imparts another straight downward movement to these members due to the straight portions 49 in the links so that the operating portion of the type band contacts the type squarely on the surface to be printed upon. Upon release of the member B, the above movement is reversed by means of the spring 54 and the operating portion of the type band again contacts the inking pad for the renewal of ink on the type.

The screws 40 may be manipulated to adjust the carrier D in the frame C and thereby adjust the face of the type in relation to the abutting edges of the flanges 23.

Since the members 36 can float in the frame C in my invention, all possibility of binding is eliminated between either the frame C or the carrier D or between the screws and the frame C or the carrier D or both and this possibility of elimination is attained by the usual formation operation of the members and without any additional cost above the usual production cost thereof.

Since my invention provides a lock means for the screws 40, there is no possibility of the screws moving and destroying the adjustment of the type during the usual pounding effects on the type. The ends of the wire of the springs resiliently engage the serrations in the heads of the screws and thereby hold the screws against rotation thereof during the use of the device but permit the screws to be rotated by exterior means without manipulating or otherwise paying any attention to the screw locking means.

My invention provides the fewest possible parts; the parts themselves formed for economical production; all parts formed and arranged so that they can be made economically and assembled economically; floating means to prevent binding between the adjusting screws and the type frame and the type carrier; cushioned abutment means for the type; and lock means for the adjusting screws to retain the type in proper adjustment during the use of the device but permitting the manipulation of the adjusting screws without paying any attention to the lock means.

I am aware that changes may be made in the structure and in the arrangement of the elements as shown and described within the scope of the appended claims; therefore, without limiting myself to the precise structure and arrangement of elements as shown and described, I claim:

1. A stamping device including a type car-

- rier and a one piece type frame formed with a base portion and a pair of leg portions depending from said base portion and a pair of ears depending from each of the leg portions and located to guide said type carrier sidewise of the device.
2. A stamping device including a type frame having opposed pairs of guide ears and a one piece type carrier formed with a pair of guide portions each having parallel edges extending between and guided in one of said pairs of ears and a flange portion on one end of each guide portion and a portion connecting the other ends of the guide portions.
3. A stamping device having a type frame made of one piece of material formed with a base portion having an opening through the same and a pair of leg portions depending from said base portion and a pair of guide portions depending from each of the leg portions and each having an opening through the same, a type carrier made of one piece of material formed with a pair of guide portions guided in said guide portions and in said opening in said base portion and a flange portion on one end of each guide portion, a nut between each of said pairs of guide portions, each of said nuts having lugs extending through said openings in said guide portions, and a screw threaded into each of said nuts and the heads thereof abutting the respective of said flange portions.
4. A stamping device having a type frame, a type carrier movable in relation to said frame, a screw to vary the relation between said frame and said carrier and having a head with serrations therein, and a coil spring over the body of said screw and between said frame and said carrier and one end thereof arranged to engage said serrations.
5. A stamping device having a type frame, a type carrier movable in relation to said frame, a member floatingly carried by said frame, a screw threaded into said floating member and engaging said carrier, and lock means anchored in said type carrier and normally engaging said screw to hold the same against rotation thereof in either direction during the operation of the device.
6. A stamping device having a type frame having a pair of guide ears, a type carrier guided by said ears, a member floatingly held by said ears, and a screw threaded into said member and journaled in said carrier.
7. A stamping device having a type frame having a pair of ears, a type carrier guided by said ears, a member floatingly held by said ears, a screw journaled in said carrier and threaded into said member in alignment with said guide and having a serrated surface, a spring tending to move said frame and said carrier in alignment with said guide, and one end of said spring engaging said serrations

to prevent the rotation of said screw during the operation of the device.

8. A cushioning means for a stamping device comprising a trough, a trough opposite the first said trough and abutting the type of the device, and a cushioning means between said troughs.

9. A cushioning means for a stamping device comprising a trough, a trough telescoping over the open side of the first said trough and abutting the type of the device, and a spring between said troughs normally tending to separate the same.

10. A stamping device having a type carrier provided with a trough having the open side thereof disposed toward the type of the device, a trough opposite the first said trough and having the closed side thereof disposed toward said type and contacting the same, and a spring between both of said troughs normally tending to separate the second said trough from the first said trough.

11. A stamping device having a type frame provided with a pair of guide ears on each end thereof and a guide opening in alignment with and spaced from each of said pairs of ears, and a type carrier having a guide portion on each end thereof and guided in the respective of said ears and said openings.

12. A stamping device having a type frame provided with a pair of guide ears on each end thereof and a guide opening in alignment with and spaced from each of said pairs of ears, a type carrier having a guide portion on each end thereof and guided in the respective of said ears and said openings, a member floatingly held between each of said pairs of ears, a screw threaded into each of said floating members in alignment with said guides and abutting said carrier, and each of said screws individually rotatable to adjust the face of the type of the device into desired relation with other parts of the device.

13. A stamping device having a type frame having guide means, a movable type carrier guided in said guide means, a pair of members each floatingly held to said frame, and a pair of screws each threaded into the respective one of said floating members and journaled in said carrier.

14. A stamping device having a type frame provided with guide means, a movable type carrier guided in said guide means, a pair of members each floatingly held to said frame, a screw threaded into each of said floating members and journaled in said carrier, and a spring between each of said floating members and said carrier and each engaging one of said screws to prevent the rotation thereof during the use of the device.

15. A stamping device having a type frame provided with guide means, a movable type carrier guided in said guide means, a pair of members each floatingly held to said frame, a screw threaded into each of said floating mem-

bers and journaled in said carrier and having a head abutting the outside of said carrier, and a spring between each of said floating members and the inside of said carrier and each engaging one of said screws to prevent the rotation thereof during the use of the device.

16. A stamping device having a type frame, a type carrier adjustable in said frame and guided therein, and adjusting means to vary the relation between said frame and said carrier and floatingly mounted to prevent binding of said carrier in the guide thereof.

17. A stamping device having a type frame, a type carrier adjustable in said frame and guided therein, adjusting means to vary the relation between said frame and said carrier and floatingly mounted to prevent binding of said carrier in the guide thereof, and resilient abutment between the type of the device and said carrier.

18. A stamping device having a main frame, a link hinged to said main frame and having a slot composed of two straight portions and an arcuate portion connecting the straight portions, a type carrying mechanism in said main frame and having a pin engaging said slot, a shaft extending through said main frame and through said slot and through said type carrying mechanism, and an operating member engaging said shaft to move the same laterally.

19. A stamping device having a main frame, a link hinged to said main frame and having a slot composed of two straight portions and an arcuate portion connecting the straight portions, a one piece type frame in said main frame and having a pin engaging said slot, a one piece type carrier adjustable in and guided in said type frame, type means in said type carrier, a floating adjusting means between said type frame and said type carrier, lock means to retain said floating adjusting means in adjusted position during the operation of the device but permitting the manipulation of said adjusting means without paying any attention to the lock means, cushioning means for the operating portion of the type on the device, a shaft extending through said main frame and through said slot and through said type frame and through said type carrier, and an operating member engaging said shaft to move the same laterally.

55 In testimony of the foregoing I affix my signature.

PETER GRABLER.
